US0D1021123S

(12) **United States Design Patent** (10) Patent No.: **US D1,021,123 S**
(45) Date of Patent: ** Apr. 2, 2024

(54) **FACIAL MASSAGER**

(71) Applicant: **ASA UNIVERSAL INC.**, Woodland Hills, CA (US)

(72) Inventor: **Sujata Bahri**, Santa Monica, CA (US)

(73) Assignee: **ASA UNIVERSAL INC.**, Woodland Hills, CA (US)

(**) Term: **15 Years**

(21) Appl. No.: **29/820,417**

(22) Filed: **Dec. 22, 2021**

(51) LOC (14) Cl. **24-01**

(52) U.S. Cl.

USPC **D24/215**

(57) **CLAIM**

The ornamental design for facial massager, as shown and described.

DESCRIPTION

FIG. 1 is a front perspective view of a facial massager in accordance with the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The "SONAGE" indicia shown in broken lines are for the purpose of illustrating environmental structure, which form no part of the claimed design.

1 Claim, 4 Drawing Sheets
